UNITED STATES PATENT OFFICE

FRANK HINMAN PIERPONT, OF SALFORDS, HORLEY, ENGLAND, ASSIGNOR TO LANSTON MONOTYPE MACHINE COMPANY, OF PHILADELPHIA, PENNSYLVANIA, A CORPORATION OF VIRGINIA.

TYPE-CASTING MACHINE.

1,094,678.

Specification of Letters Patent. Patented Apr. 28, 1914.

Application filed November 13, 1912. Serial No. 731,191.

To all whom it may concern:

Be it known that I, FRANK HINMAN PIERPONT, a citizen of the United States, residing at Salfords, Horley, in the county of 5 Surrey, England, have invented a certain new and useful Improvement in Type-Casting Machines; and I do hereby declare the following to be a full, clear, and exact description of the same, reference being had to 10 the accompanying drawings, forming a part of this specification, and to the figures and letters of reference marked thereon.

This invention relates to die or die-case 15 positioning or centering mechanism for type-casting and composing machines of the class wherein a die-case or carrier is moved by the die-case positioning mechanism to position a selected die or matrix therein over a mold, after which the selected die or matrix 20 is centered and clamped upon the mold for a cast to be made therefrom.

The matrices or characters in the die-case are arranged in rows running in two directions and the die-positioning movements of 25 the die-case are effected by positioning or adjusting mechanism controlled by the gage pins, stops or their equivalent which are governed generally by a record strip or controller, and after the die case has been 30 moved, to position a selected character or matrix over the mold, a centering pin engages the matrix, generally by entering an opening or cavity therein, and finely adjusts it and clamps it on the mold for the cast to 35 be made.

The centering distance between matrices or characters in a standard or normal die-case has hitherto been constant and equal to or in proportionate relation to the distance 40 between successive gage pins or stops, the distance between which has also been constant.

With machines so equipped, various die-cases each for a different size of font may 45 be employed, but the constant distances between the gage pins of the positioning mechanism and the constant centering distance 50 between matrices, places a limit upon the maximum size of the characters or font that can be produced, without involving consid-

erable structural alterations in the machine, or the provision of a separate machine for separate sizes of fonts.

While a machine equipped with the usual die-case positioning mechanism and with 55 die-cases having matrices of normal dimensions or with normal centering distances meets general commercial requirements it is sometimes necessary or desirable to produce characters of abnormal dimensions or above 60 a certain point size, and these cannot be dealt with in the ordinary machine, for the reason that the centering distances between the matrices can no longer be normal nor bear a constant relation throughout to the 65 distance between the gage pins.

Matrices of abnormal size, having their centering distances a constant but different from the constant distance between the gage pins, can be centered over the mold, to be 70 finely adjusted by the centering pin by the usual centering mechanism, and a mechanism for varying at each position the amount of movement to be imparted to the die-case as for example by the mechanism according 75 to British Patent No. 13209/09 (U. S. Patent 1,008,364, Nov. 14, 1911) and, to a limited extent, abnormal matrices can be employed in a die-case so long as the centering cavity therein can occupy a position such 80 that the centering distance between it and a neighboring matrix is normal in accordance with British Patent No. 20554/09 (U. S. Patent No. 980,959, Jan. 10, 1911) the die-case being positioned in this case, as with 85 normal matrices.

It is the chief object of the present invention to increase the capacity of the machine and to provide for the positioning of a die-case or matrix carrier wherein the matrices are of abnormal dimensions and the centering distances are not normal, or wherein the centering distances are not constant throughout or throughout a particular row of matrices, at the same time permitting of 90 the machine being employed with die-cases having normal matrices.

According to the present invention, the die-case, after it has been positioned by the usual positioning mechanism and released 100

therefrom, has an additional movement imparted to it by a supplementary mechanism which finally positions or moves the die-case bodily to position and finely adjusts the selected matrix over the mold cavity.

The main or usual die-case positioning mechanism is selective and the supplementary mechanism moves the die-case to position the selected matrix.

10 In accordance with the present invention, there is provided on or operatively connected with the die-case or its carrier a series of teeth, inclined surfaces, or devices having the equivalent effect with which a second or 15 supplementary positioning member engages after the die-case has been adjusted by the usual positioning mechanism to finally position the die-case and finely center, over the mold cavity, the selected matrix for a cast 20 to be made.

Conveniently and preferably the inclined surfaces or teeth are formed on or in a plate placed over the die-case, and the centering pin hitherto employed for finely adjusting or centering a selected matrix is made use of to impart the additional or final positioning movement to the die-case.

The teeth or the like are conveniently formed upon or carried by a plate situated 30 on the top of the die-case and their inclined surfaces lead toward or into the centering cavities in the matrices so that the pin, after engaging the said surfaces and moving the die-case, enters a matrix cavity and finely 35 centers it and clamps it upon the molds.

Referring to the accompanying drawings, illustrating a preferred form of embodiment of said invention: Figure 1 is a top view in plan of a die-case embodying the present invention. Fig. 2 is a plan of the die-case with the top plate removed to show the matrices. Fig. 3 is a similar view to Fig. 2 showing a die-case furnished with standard matrices. Fig. 4 is a sectional elevation on the line 4—4, of Fig. 1. Fig. 5 is a section on the line 5—5, of Fig. 1. Fig. 6 is a diagrammatic view illustrating the action of the final centering mechanism, and Fig. 7 is a plan showing the die-case in position 50 on a machine of known construction.

Like figures and letters of reference in the several figures indicate the same parts.

A is the die-case frame.

B are the matrices.

55 C is a plate on or in which are the inclined positioning surfaces, D, and E is the centering device.

The machine with which the present embodiment of the invention is shown is that forming the subject matter of British Patent No. 8633/99 (U. S. Patent No. 625,998, May 30, 1899) the die-case positioning mechanism being as improved by British Patent No. 27476/03 (U. S. Patent No. 749,149, January 12, 1904), and the die-case as improved

or modified in accordance with British Patent No. 4726/05 (U. S. Patent No. 784,245, Mech. 7, 1905).

The die-case positioning mechanism, in the form in which it exists in the particular machine to which the present invention is shown applied and as described in the aforesaid specifications, comprises two sets of control mechanism operating on intersecting lines and each determining the position in one direction. Each set comprises a primary controller consisting of a series of stop pins 1 (see Fig. 7) serially arranged; a primary positioning mechanism consisting of a pair of oppositely moving jaws attached to the outer ends of levers 2, 3, which close upon the indicating stop pin; a secondary controller in the form of a bar provided with a stop 6 which stands between the said jaws and is brought to position thereby; a bolt 7 which is advanced to lock the secondary controller in position; and a secondary positioning mechanism in the form of jaws connected to the outer ends of levers 4, 5, which close upon the stop 6 and upon translating devices for the die-case A to bring the latter to the position denoted by the stops 6. Each set of levers is connected to an actuator 11, 12, connected in turn to a prime mover 9 through spring boxes.

After the die case has been moved by the positioning mechanism above described it is released by the opening of the jaws carried by levers 4, 5, and a die-centering pin E descends, entering a cavity b (see Figs. 4 and 6) in the end of the matrix B which has been roughly centered over the mold F and said centering pin finely and accurately centers the matrix over the mold cavity, holding it clamped on the mold until the cast has been made.

In these machines the character has a definite position on the matrix and with relation to the mold, and the centering pin has a fixed position for dealing with all the matrices.

The matrices are provided with side grooves b' for suspension on rods, bars or fingers b² after the manner described in the specification of British Patent No. 4726/05 (U. S. Patent No. 784,245).

In accordance with the present invention the die-case is provided with a series of inclined surfaces D with one or another of which in accordance with the adjusted position assumed by the die-case under the action of the usual die-case positioning mechanism (1, 2, 3, 4, 5, 6, 7, 9, 11, 12) the second or supplementary positioning member engages.

As above stated, the inclined surfaces D being situated over the die-case and leading into the centering cavities in the matrices, use is made of the existing centering pin E to constitute the second positioning mem-

ber. In descending, the pin E bears upon this surface D and shifts the die-case bodily so that it finally assumes a position to allow the pin to enter the centering cavity b in the 5 matrix B situated in proximity to or under the particular inclined surface D which the pin engages.

In Figs. 1, 2 and 3, the centering cavities b, in the matrices B (which are tapering or 10 conical—see Figs. 4 and 6) are for the sake of clearness indicated by a circle representing the base of the cone.

In its final or ultimate stage of movement the pin E acts to center the particular matrix 15 and clamp it upon the mold, as hitherto by seating in cavity b. In order to permit and regulate this final movement the plate C, on which the inclined surfaces D are carried or are formed, is provided with 20 circular holes or openings C' (see Figs. 4 and 6) which extend from the lower surface of the plate immediately over the openings in the matrices B to the lower edge of the inclined surfaces D. Thus the pin E 25 after moving the die case bodily, passes through the holes C' and then into the cavity b of the selected matrix.

The inclined surfaces D are conveniently cut in the plate C and surround the holes 30 C'; in plan they appear for the particular font shown approximately circular as shown in Fig. 1, and in sectional elevation they are conical, the sides in some cases being of unequal lengths and the angle varying (see 35 Figs. 4, 5 and 6) depending upon the amount of movement to be imparted to the die-case in each case by the pin E.

Taking a particular instance as existing in the present embodiment of the invention, 40 when the normal positioning mechanism has acted upon the die-case, the latter is located with a particular matrix B (see Fig. 6) which represents that selected to be centered, over the mold so that the inclined surface 45 face at a point d^{10} directly under the centering pin E is approximately the point at which the pin will first engage. The pin then descends and, engaging the inclined surface D, by its continued descent moves 50 the die-case laterally until the point d^{11} at the center of opening C' is directly under the point of the pin E which latter by its continued forward movement finally enters 55 the cavity b in the matrix and centers and clamps it upon the mold.

In a die-case with normal matrices, the hitherto maximum number of matrices for characters up to 12 point has been 225 arranged in 15 rows each containing 15 60 matrices (see Fig. 3) corresponding with the serial arrangement of the fifteen pins 1.

In the font shown in the present example (Figs. 1, 2, 7) the matrices are all abnormal and are not all of the same size. Seven 65 rows (counting from the left hand side in

Fig. 2) contain 15 matrices each and the remaining three rows contain 10 matrices each. The matrices in the first seven rows are no longer square as normal matrices are, but oblong. The centering distances between the matrices of any particular row of these seven are normal in one direction and therefore these matrices are centered over the mold in this direction of translation by one of the normal centering mechanisms. 70 In the other direction the centering distances between these particular rows is not normal and therefore in this direction of translation the matrices are not positioned by the normal positioning mechanism alone, 75 but by the normal positioning mechanism and in addition by supplementary mechanism E, D.

The matrices of the three remaining rows, i. e., the three right hand rows (see Fig. 85 2) are square but are of abnormal size. neither the centering distances between matrices of a row nor those between rows are normal; further, the centering cavities b are not central of the matrices. All the 90 matrices of these rows require the positioning movements of the normal positioning mechanism and the supplementary mechanism E, D, to center them over the mold cavity, in both directions of translation. 95

In Fig. 1 the relative position of the pin E and the matrix after the die-case has been adjusted by the normal positioning mechanism and after the supplementary mechanism has acted, is shown. The points X indicated at d^{10} represent the points at which the pin E will engage the surface D after the die-case has been positioned by the normal mechanism, and the point + indicated by d^{11} represents the central point of the 100 centering cavity of the matrix after the die-case has been moved by the pin E. The distance through which the die-case is moved in each case by the pin E is therefore the distance between the points X and + in each 105 case.

The present arrangement lends itself well to the requirements of the class of low quad mold operating mechanism, of which examples are to be found in Patents No. 962,412, 115 June 28, 1910, and No. 989,637, April 18, 1911, wherein the projection of the cut-off member is indicated and effected by the presentation of a matrix with a relatively shallow centering cavity, whereby the centering pin is arrested at an earlier point in its seating stroke.

In the present instance said shallow seats 20, Fig. 1, may be formed in plate C at a point or points intermediate adjacent openings D C' and registering with one of the unused pins 1 of the centering mechanism. 125

It will be seen that the pitch of the spacing devices of the supplemental positioning mechanism represented by inclines D and 130

associated perforations C' differs from that of the selective positioning mechanism represented by stop pins 1, and that the stations C' of the supplemental positioning mechanism are controlled or designated by said stop pins. Thus in the machine illustrated each of the selective positioning mechanisms for effecting adjustments of the die case on intersecting lines contains fifteen equally spaced pins 1 each designating a separate station in the direction of movement controlled thereby, while the supplemental positioning mechanism possesses but ten stations, counting from left to right in Fig. 1, and fifteen stations for seven rows reading from top to bottom of the drawing and ten stations for the remaining three rows.

By a proper selection of pins 1 of the two series the die case can be adjusted to bring the incline D of the desired station C' in operative relation to the centering pin E, as indicated by the X's in their relation to the +'s in Fig. 1. For example, the movements of the die case from right to left in Fig. 1 to bring any one of the ten stations C' of the supplemental positioning mechanism in operative relation to the complementary engaging member represented by the centering pin will be performed successively by the first, third, fourth, sixth, seventh, ninth, tenth, twelfth, thirteenth and fifteenth stop pins 1, and in the case of the three right hand columns of station C' the same numbered pins 1 of the other series will serve to designate successive stations; in other words the pins of the two selective positioning mechanisms designating stations in the two systems located and falling within the area of the incline D adjacent any one of the perforations C' may be employed to bring the selected perforation or station of the supplemental positioning mechanism in operative relation to the complementary engaging member or centering pin E, so that upon the advance of the latter the die case will be shifted from the station primarily indicated by the selective positioning devices to that indicated by the corresponding member of the supplemental positioning mechanism. It will be further noticed that the supplemental positioning mechanism represented by plate C with its station designating openings C' and directing inclines D for coöperation with the centering pin is responsive to the two selective positioning mechanisms when acting either singly or in conjunction, and operates to translate the station adjustments of the die case as measured or determined by the selective positioning mechanisms into those of the supplemental positioning mechanism, hence by a mere substitution of die cases and without other change by way of addition or subtraction the spacing normal to the selective po-

sitioning mechanism can be translated into 65 that of the selected die case. That is to say by applying the supplemental positioning mechanism to the performing member, *i. e.*, the die case, whose position is determined by the conjoint action of the two signal controlled selective positioning mechanisms, the latter are utilized for designating the stations of the supplementary positioning mechanism which are subsequently attained through the engagement of the plunger with 70 the incline leading to the indicated station.

Having thus described my invention, what I claim as new is:

1. In a type casting machine provided with a movable die case and selective positioning mechanism therefor equipped with spacing means and in combination therewith, a supplemental positioning mechanism coupled with the die case and provided with spacing means differing in pitch or measure 80 from that of the selective positioning mechanism and operating to automatically shift the die case from the station to which it is carried by the selective positioning mechanism to one of the stations of the supplemental positioning mechanism.

2. In a type casting machine equipped with a movable die case and selective positioning mechanism therefor of a predetermined pitch or measure for designating different stations for the die-case, and in combination therewith, a supplemental positioning means coupled with the die case and equipped with spacing means differing in pitch or measure from that of the selective 95 positioning mechanism and a complementary engaging member, said selective positioning mechanism operating through the die case to selectively designate different stations of the supplemental positioning means.

3. In a type casting machine, the combination of the following elements, *to-wit*: a two-way movable die case; a duplex selective positioning mechanism, each section whereof is coupled with the die case to move 100 the latter in a direction transverse of the other and is provided with spacing means of a predetermined pitch or measure; and a supplemental positioning means coupled with the die case and provided with spacing 115 means differing in pitch or measure from that of the selective positioning mechanism, said supplemental positioning means operating to displace the die case from the indicated station of the selective positioning 120 mechanism to a station of the supplemental positioning means.

4. In a type casting machine provided with a movable die case and a selective positioning mechanism therefor provided with 125 spacing means of a given pitch or measure, and in combination therewith, a supplemental positioning means of a different

pitch or measure from that of the selective positioning means, the same including a member coupled with the die case and provided with a series of inclined surfaces terminating at points out of register with the indicated stations of the selective positioning mechanism, and a plunger coacting with said inclined surfaces to effect a displacement of the die case from the station of the selective positioning mechanism to one of said supplemental positioning means.

5. In a type casting machine the combination of the following elements, to-wit: a movable die case; a selective positioning mechanism coupled with said die case and operating to position the latter at any one of a given series of stations; and a supplemental positioning mechanism whose pitch or measure differs from that of said selective positioning mechanism, the same including a plate provided with a plurality of perforations and marginal inclines disposed serially in the direction of movement of the die case and coupled with the latter, and a plunger adapted to engage said marginal inclines and shift the die case from the station to which it is assigned by the selective posi-

tioning mechanism to that one indicated by the perforation adjacent the engaged incline.

6. In a type casting machine provided with a movable die case containing a plurality of matrices serially arranged, a centering plunger with relation to which the die case is movable, and a selective die case positioning mechanism provided with an admeasuring means of predetermined pitch or measure, and in combination therewith, a supplemental positioning mechanism of different pitch or measure from that of the selective positioning means the same including a plate coupled with the die case and interposed between the contained matrices and plunger, said plate being provided with a plurality of perforations and adjacent inclines serially disposed in the direction of movement of the die case by the selective positioning mechanism but differing in number and pitch or measure from the admeasuring means of said selective positioning mechanism.
